UNITED STATES PATENT OFFICE.

ARCHIBALD GRAINGER AND ERNST KLEPSCH, OF SAGINAW, MICHIGAN.

BLOCK.

No. 844,123.

Specification of Letters Patent.

Patented Feb. 12, 1907.

Application filed April 17, 1906. Serial No. 312,277.

To all whom it may concern:

Be it known that we, ARCHIBALD GRAINGER and ERNST KLEPSCH, citizens of the United States, residing at Saginaw, W. S., in the county of Saginaw and State of Michigan, have invented new and useful Improvements in Blocks, of which the following is a specification.

This invention relates to blocks or holders for printing purposes, the object of the invention being to provide a block or holder especially designed with reference to clamping stereotype or electrotype plates of different sizes and shapes in place, whereby the clamping of such plates is greatly facilitated and the clamping devices which hold the plate in place are rendered easily adjustable to any desired angle, the clamping devices being easily and rapidly operated for clamping and releasing the stereotype or electrotype plate, thus saving valuable time.

With the above general object in view the invention consists in the novel construction, combination, and arrangement of parts, hereinafter more fully described, illustrated, and claimed.

In the accompanying drawings, Figure 1 is a top plan view of a block embodying the present invention. Fig. 2 is a bottom plan view of the same. Fig. 3 is a cross-section through one end of the block. Fig. 4 is a cross-section extending transversely through one side or end of the block. Fig. 5 is a detail plan view of one of the clamping-shoes.

The body 1 of the block or holder may be of any desired size as to width and length, and under the preferred embodiment of this invention the body of the block or holder is recessed on its under side, as shown at 2, for the sake of lightness, the recessing of the under side of the block being carried out, preferably, in such manner as to leave inwardly-extending bearing portions 3, which receive the retaining devices by which the jaw or block carriers are held in place, as will hereinafter appear. In its upper or opposite face the block or holder is provided with a number of circular bearing-recesses 4, in each of which is mounted a swiveled or rotatable jaw or block carrier 5 in the form of a disk, the same being provided in its periphery with an annular groove or seat 6, as shown in Figs. 3 and 4. Mounted on each of the carriers 5 near the periphery thereof, is a clamping-jaw or block 7, having a shank 8, which is journaled in a corresponding opening in the carrier,

which shank terminates in a head 9, countersunk in the carrier, as shown in Fig. 4, so as to hold the jaw or block 7 in place. By the arrangement described it will be seen that each of the blocks or jaws 7 has a swivel-jointed connection with its respective carrier, whereby said jaw or block may dispose itself at the proper inclination to bear firmly throughout its entire length against the lateral edge of the stereotype or electrotype plate shown at 10.

The clamping mechanism for holding each of the carriers 5 from rotation is shown as comprising a segmental clamping-shoe 11, which fits in the annular groove or seat 6, having a notch 12, which receives a tongue 13 at one end of a slide 14, which works in a groove 15 of a corresponding shape in the face of the block or holder. The opposite or outer end of each slide is provided with a beveled or inclined shoulder 16, which is acted upon by the conical shoulder or portion 17 of a clamp-actuating device 18, shown in the form of a beveled-headed screw, the threaded shank 19 of which is received in the correspondingly-threaded opening or socket in the block, as clearly shown in Fig. 3. By turning the screw 18 with an ordinary screw-driver in the usual manner the screw is raised or lowered, and when tightened said screw co-operates with the inclined shoulder of the slide 14 and forces the slide toward the carrier 5 and acts to press the shoe 11 into binding engagement with said carrier, thus preventing the carrier from turning and holding the clamping jaw or block 7 thereof firmly against the electrotype or stereotype plate.

Upon loosening the screw 18 the pressure of the slide 14 against the carrier is relieved, thus permitting said carrier to be turned for releasing the plate.

Instead of employing a shoe 11 in connection with each slide the slide may be shouldered, as at 20, to bear directly against the adjacent carrier, the principle involved being exactly the same. The shoes 11 are ordinarily preferred, however, as they give an increased bearing and binding surface and more securely protect the carriers against turning.

By loosening the clamp-actuating devices 18 the carriers 5 are free to be turned in either direction, and by thus turning or adjusting the carriers the clamping-jaws or blocks 7, swiveled thereon, may be moved to-

ward and away from each other and brought to the desired relative positions to receive and hold the plate 10 between them. It will be observed that the plate 10 may be clamped either centrally of the block or toward one side or end thereof, or said plate may be clamped at various angles. Also plates of various sizes may be clamped upon the block by the means described, thus enabling a single block to be used for printing-plates of many sizes and shapes.

Each of the carriers 5 is shown as held in place by a retainer 21 in the form of a screw passing through an opening in one of the bearing portions 3 at the under side of the block and into the overlying carrier 5, as clearly shown in Fig. 4, thus permitting the carrier to turn, but holding the same in the bearing-recess in which it is stepped. Any suitable retaining means may be substituted for the screw 21.

We claim—

1. A block or holder for printing-plates comprising a plurality of swiveled carriers, 25 clamping jaws or blocks held by said carriers, and slides movable toward and away from the edges of the carriers for clamping the same.
2. A block or holder for printing-plates comprising a plurality of swiveled jaw-carriers, 30 clamping - jaws mounted thereon, a clamping-slide engaging each carrier, and a

clamp-actuating device coöperating with said slide.

3. A block or holder for printing-plates 35 comprising a plurality of swiveled jaw-carriers, clamping-jaws mounted thereon, a slide for holding each carrier, and a clamp-actuating device for operating the slide, said clamp-actuating device and slide having 40 inclined coöperating shoulders.

4. A block or holder for printing-plates comprising a plurality of swiveled jaw-carriers, jaws carried thereby, slides engaging the carriers, and clamp-actuating devices in 45 the form of screws having a threaded engagement with the body of the block or holder and provided with inclined shoulders which coöperate with corresponding shoulders on the slides.

5. A block or holder for printing-plates comprising a plurality of swiveled jaw-carriers, jaws carried thereby, slides for holding the carriers, clamping shoes interposed between the slides and carriers, and clamp-actuating devices coöperating with said slides to shift the same.

In testimony whereof we affix our signature in presence of two witnesses.

ARCHIBALD GRAINGER.
ERNST KLEPSCH.
